UNITED STATES PATENT OFFICE.

HENNING SUNDQUIST, OF CHICAGO, ILLINOIS.

LOCKING-LATCH.

SPECIFICATION forming part of Letters Patent No. 293,987, dated February 19, 1884.

Application filed March 5, 1883. (Model.)

To all whom it may concern:

Be it known that I, HENNING SUNDQUIST, a subject of the King of Sweden, residing at Chicago, in the county of Cook and State of Illinois, have invented certain new and useful 5 Improvements in Locking-Latches, of which the following is a specification.

This invention relates to locking-latches; and it consists in providing the lock with a 10 lever one end of which is adapted to be thrown behind a projection on the latch as the other end is thrown out of a transverse slot in the hollow lock-spindle by means of a shaft located within the spindle and turned by a key, substantially as hereinafter more fully described.

15 In order to enable others skilled in the art to which my invention appertains to make and use the same, I will now proceed to describe its construction and operation, referring to the 20 accompanying drawings, in which—

Figure 1 is a face view of my lock with the side plate removed. Fig. 2 is a longitudinal section on the line xx , Fig. 1. Fig. 3 is a view of the latch-operating arm; Fig. 4, a view of 25 the locking-spindle; and Fig. 5 represents the key.

A represents the lock-case, which is provided with the latch B, formed with two arms or projections, $b b'$, against the former of which 30 bears the operating-spring B', as shown by Fig. 1. The rear end of the latch B is slotted, as represented by dotted lines, for the reception of the operating-arm c upon the sleeve C, secured to the knob-spindle D, and by which 35 the latch is withdrawn when desired. The spindle or shaft D is hollow, and carries upon each end the knobs D' D', formed with an opening, d, for the insertion of the key into the spindle.

40 Within the case A is pivoted a lever, E, one arm of which extends forward and is adapted to be thrown behind the arm b' of the latch, to prevent its withdrawal, and the other arm

extends back and lies normally in a transverse slot, e, cut through the sleeve C and hollow 45 spindle D. This lever is also formed with a stud, e', against which bears the spring E', as shown.

Within the hollow spindle D is placed a loose shaft, G, formed with a central transverse slot, g, corresponding to the slot e in the spindle, and upon each side of this slot with a circumferential groove, g', for the reception of the ends of small screws g², extending through the spindle D, and serving to retain 55 the shaft G in place. Each end of the locking-shaft G is formed with notches or other configuration for engagement with a key, N, which may be inserted through either of the knobs D' D'. Normally, the inner arm of the 60 lever E lies in the slots e g of the spindle and its sleeve, and the latch is free to operate as the knob is turned; but when the key is inserted and the shaft G is turned half-way round, the inner arm of the lever E is thrown out, 65 thereby throwing the other end behind the projection b' of the latch B, and effectually preventing its being withdrawn.

Having thus fully described my invention, what I claim as new, and desire to secure by 70 Letters Patent, is—

In a locking-latch, the combination, with a latch formed with a lug upon one side and a hollow spindle or knob shank having a transverse slot formed in it, of a revolving slotted 75 shaft within the hollow spindle, and a lever adapted to lock the latch by the turning of said shaft, substantially as and for the purpose set forth.

In testimony whereof I affix my signature in 80 presence of two witnesses.

HENNING SUNDQUIST.
